UNITED STATES PATENT OFFICE.

HUGH NELSON HURD OF BUFFALO, NEW YORK.

SPEED-CONTROLLING SYSTEM FOR MOTORS AND THE LIKE

Application filed July 14, 1919. Serial No. 310,763.

To all whom it may concern:

Be it known that I, HUGH N. HURD, a citizen of the United States, residing at Buffalo, in the county of Erie and State of New York, have invented new and useful Improvements in Speed-Controlling Systems for Motors and the Like, of which the following is a specification.

This invention relates to an improved method of maintaining a predetermined definite operating relation between independent motors or prime movers whereby power may successfully be transmitted to separated machines or apparatus to operate the latter in a definite speed relation in predetermined ratio and with compensation for variation in the load in driven machines, apparatus or power consuming devices. My improved method and controlling means is applicable to cause one or more motors, engines, pumps or other rotating apparatus to maintain a definite speed relation to each other, maintain a balance between loads and speeds of hoists or like apparatus or to maintain a constant speed or load between independently driven devices for the improvement of the load factor.

An important feature of my invention consists in employing independent prime movers to drive separated machines or apparatus and utilizing the differential pressures between the respective prime movers or means associated therewith to energize a controlling and regulating means suitably connected with one of the prime movers to control its operation whereby said latter prime mover automatically and positively is controlled to operate in a definite and predetermined ratio with the other of the prime movers throughout any variations resulting from the load or rise and fall in the source of energy. As a result throughout the entire operation and under varying degrees of the load definite relative driving forces will be transmitted to the respective driven machines so as to maintain a constant or fixed speed ratio in their operation.

My improved method and means of control is particularly adapted for the driving

or separate machines or apparatus which operate in succession upon a product and where it is desirable to maintain a continuity of operation in a predetermined relation such as is required for instance in the rolling of sheets, metal bars, rods, wire, etc. In the installations of the specified character, as will be understood, the material such as a bar is progressively reduced by being passed through successive sets of rolls or roll stands and to maintain the proper continuity of operation these various pairs of rolls are driven in a speed relation the ratio of which is determined by the cross section of the bar operated on by the respective pairs of rolls. In consequence of the reduction of the bar in successive stages the peripheral speed of the respective rolls must progressively increase. Therefore to maintain the proper speed of the bars through the mill a relative speed relation must be maintained and this predetermined relation, as will be readily appreciated, is subject to disturbance in consequence of variations in the load and in the driving forces.

As heretofore practiced in installations of this type it has been customary for the purpose of maintaining a predetermined ratio between devices to accomplish this result by means of mechanical driving connections involving a large expenditure for installation and maintenance and further in connection with which a change in ratio could only be made at considerable expense and with a resulting loss of time.

The improved method and controlling means of my invention permits of the successful use of independent prime movers for the respective rolls or other apparatus and not only automatically maintains a fixed operating ratio therebetween but further compensates for variations in the speed resulting from load and a rise and fall in the respective sources of power and moreover is regulable to permit of readily changing the ratio when desired. The latter feature permits of changing the predetermined ratio to be maintained in proportion to the adjustment of the rolls, permits of adapting the rolling operation to roll different sections

and further my improved controlling means permits of a change in ratio being effected during the rolling operation if required.

In the application of the principles of my invention as a preferred embodiment thereof I desirably employ electrically operated controlling means for the respective prime movers or motors energized by the potential drop or differential electrical pressures between controlling circuits associated with the respective prime movers. Desirably the independent prime movers may be electric motors directly connected to drive rolls or other apparatus and suitable small generators may be mounted upon the shaft of each of the driving motors and the difference of potential between the respective generator circuits may be employed to energize the controlling means; the controlling means in an arrangement of this character being operative to actuate a rheostat for regulating a resistance in the field circuit of the motor to be controlled.

While as aforesaid my improved method of control by the employment of differential or unbalanced pressures automatically to restore the balance or predetermined ratio is particularly adaptable for the driving of stands of rolls it will be understood that this improved method of my invention may be employed with many and various types of machines and apparatus where it is desirable to maintain a proper sequence in the operation and definite speed ratio therebetween. Furthermore, my improved principles of operation may be employed with sources of energy of any suitable character either electrical as referred to or in connection with fluid pressures such as steam, hydraulic or air where in like manner the differential pressure is instrumental in maintaining the proper ratio in the speed of the moving apparatus throughout the entire speed range of operation.

The described and other features and advantages of my invention will be understood by reference to the accompanying drawings wherein there are shown diagrammatically suitable embodiments of my improved principles and wherein like reference numerals are applied to the corresponding parts or devices in the several views.

Referring to the drawings:

Fig. 1 is a diagrammatic view of a desirable embodiment of my invention wherein the prime movers or driving motors are of unlike character and have associated therewith electrical generators directly connected to or carried by the respective motor shafts and arranged whereby the difference of potential therebetween will energize an electrical controlling means connected to regulate the operation of one of the prime movers with respect to the other.

Fig. 2 is a similar diagrammatic view

illustrating a modified arrangement wherein the controlling motor is driven by an independent source and has a pole changer associated therewith and arranged to be operatively responsive to the controlling circuit.

Fig. 3 is a diagrammatic view illustrating a further modification in the operating means for the controlling rheostat wherein a continuously operating motor is employed for adjusting the rheostat.

Fig. 4 is a diagrammatic view of a further modification wherein the operation of the controlling rheostat is arranged to be responsive to changes or variations in the value of the controlling circuit.

Fig. 5 is a similar view illustrating a modified arrangement wherein controlling rheostats are associated with each of the driving motors and operative in inverse relation by means of the controlling circuit.

Fig. 6 is a diagrammatic view indicating the manner in which unbalanced fluid pressures may in similar manner be employed to regulate one of the prime movers so as to restore the balance or predetermined ratio.

Fig. 7 illustrates a further modified embodiment of my invention wherein governor means are arranged to be responsive to the speeds of the driving motors and connected to operate the controlling rheostat in differential manner.

Fig. 8 illustrates an arrangement of my invention wherein a differential controlling circuit is employed to effect the closing and opening of an additional circuit or supplementary source of energy.

Referring to the drawings, in Fig. 1 there is illustrated diagrammatically an approved installation employing the principles and features of my invention in an arrangement which I have successfully reduced to practice in the driving of successive pairs of rolls adapted for rolling steel bars. In this installation of my improved method I have controlled the operation of a motor driving the so-called sizing rolls with relation to the operation of a motor driving the finishing rolls so as to maintain a predetermined speed ratio between the respective rolls which operate in succession upon the bar.

In the arrangement of Fig. 1 as shown A and B are the prime movers consisting respectively of independent electric motors, of which as actually used, A is driven by an alternating current circuit and B by a direct current circuit; the former being connected to drive the finishing roll stand 1 and the latter being connected to drive the sizing roll stand 2 or last pass in the rolling operation. For the purpose of employing variations in the energies of the respective prime movers or motors A and B to restore the proper ratio therebetween, where as disclosed the operating circuits are of unlike

character, there is associated with each of the motors A and B a small d. c. generator C and D. In the arrangement as disclosed the armatures of generators C and D are desirably mounted directly on or connected to the armature shafts of the motor A and B respectively.

In accordance with my invention it is arranged that any difference in potential between the circuits of the respective generators C and D will operate through a controlling circuit 4 to energize controlling means operative to regulate one of the main driving motors, as here shown the motor B. The controlling circuit may be connected to the positive or negative sides of the generator as desired. The controlling means may desirably regulate the operation of the motor B by adjusting the value of a resistance in its field exciting circuit which may be accomplished as here disclosed by means of a rheostat R in series with the field exciting circuit of the motor B as shown. The controlling arm of the rheostat may desirably be moved in one direction or the other to vary the resistance under control of a small motor E which is energized by the controlling circuit and is made responsive to any differences in potential between the aforesaid generators C and D.

The operating connections between the controlling motor E and the rheostat adjusting arm may consist of any suitable connections and the controlling motor E may desirably be of a reversing type, whereby the rotation of its armature in one direction or the other, depending upon the direction of current flow in the controlling circuit, will transmit its motion to the rheostat arm so as to increase or decrease the resistance in the field excitation of the motor B.

The generators C and D are of a type which under normal conditions will vary in their voltage output only in direct proportion with changes of speed or in response to hand adjustment to determine the relative speed ratio to be maintained. In the arrangement disclosed the field circuits of the motors A B and E and also of the generators C and D are all separately excited. However, the field exciting coils of generators C and D and of the motor E are energized from the same circuit 5 so that there will be no variation in the relative operation of these respective devices by reason of differing fluctuations in their fields. At r , r there are indicated suitable adjustable resistances or rheostats in series with the field coils of the respective generators C and D by the adjustment of which the ratio of field flux of the generators C and D relative to each other may be regulated and in consequence the speed ratio determined.

In the operation of the system as described it will be understood that the motors

A and B, which may be considered the prime movers, may be widely separated in their relative locations and may be driven by independent electrical sources of power. They are thus subject to variation in their operation in response to variations in their energizing circuits and also under variations of load reactions. Under normal conditions upon the rotation of the armatures of the motors A and B in their predetermined speed ratio, it is designed that the generators C and D shall produce electrical currents of like value so that there shall be balanced potential energies and in consequence no current flow in the controlling circuit 4. As will be further understood the relative speeds of the driving armatures of the motors A and B to effect the generation of balanced energies is determined by the adjustment of the field resistance r of the generators C and D. The ratio thus established thereafter will be maintained automatically through the action of the controlling means or rheostat R. In so operating it will be understood that the controlling means will be so connected that upon being energized by a flow of current in one direction or the other it will operate the rheostat R to govern or regulate the motor B in a manner to compensate for any disturbance in the speed ratio of the driving armatures. This effect is accomplished by introducing additional resistance in the exciting field of the regulated motor B when the armature thereof tends to decrease its speed or to cut out resistance proportionate to any tendency to increase its speed with relation to the armature of A from that of the predetermined ratio.

In so maintaining the balanced speed relation between the armature of motors A and B, the controlling means as aforesaid will be responsive to any differences in the potential values of the generator circuits and will be instantaneous in its action to restore the proper relative speed ratio irrespective of variations in the speed of operation. In other words the constant relative speed of the respective motors will be maintained throughout the entire range of operating speeds under varying conditions of load or of rise and fall in the power.

The arrangement as described thereby employs the unbalanced energies to restore the balance of the independent prime movers by the regulation or governing of the one with relation to the other so as to compensate for any disturbance of the determined ratio caused by variations in the rotary speed of one or the other of the prime movers whether such variation is caused by rise and fall of the driving forces, change of field flux, change of armature shunt or change of speed under varying load conditions to which one or the other of said prime movers is subjected.

To more specifically define the operation of my improved method of control it will be assumed in the first instance that the prime movers A and B are each directly connected to drive rolls and that the rheostats have been properly adjusted to maintain the required speed ratio of their operation. Under normal conditions and relations of the driving efforts the driving forces transmitted to the respective stands of rolls will operate the rolls in their proper speed relation and in consequence there will be no flow of current in the controlling or differential circuit 4. Assuming under these conditions that a disturbing factor is introduced in the operation of one or the other of the motors, for instance a variation of load or should the motor B be subjected to a load of excessive value and in consequence 10 there will be a slowing up of its armature and accordingly there will be a flow of current from the generator C of the motor A resulting from its relatively increased speed with respect to the generator D. The effect 15 thereof will be to operate the motor E to transmit a rotary effort to the rheostat arm of the controlling rheostat R in a direction to increase the resistance in the exciting field of the motor B. As a result the rotary 20 effort of the latter motor will be built up or increased to compensate for the variation in load and to restore and maintain the proper relative speeds.

While I have shown and described in connection with Fig. 1 a desirable arrangement or system employing the features of my present invention it will be understood that the same is subject to various modifications without departing from the substance 25 of my invention. Accordingly I have illustrated in Fig. 2 a suitable modification wherein the controlling motor E, connected to the regulating rheostat R, is arranged to be operated by the current of an independent energizing circuit 10, the latter circuit being arranged to be closed by means of a suitable pole-changer P arranged to be actuated by a relay circuit 11 associated with a Thompson balance circuit closer T arranged to be 30 responsive to the controlling or differential circuit 4. In this arrangement, as indicated, 12, 12 indicate the stationary coils of the Thompson balance arranged in series with a shunt circuit 13 connected to the exciting circuit 5. 14, 14 indicate the movable coils of the Thompson balance carried by a pivotal switch arm 16 and connected in series with the differential controlling circuit 4. At 17 there are indicated the movable contacts carried by the arm 16 and adapted to 35 close the circuit 11 by engagement with terminals 18 or 19 whereby circuit 11 is closed either through branch 20 or branch 21 for energizing magnets 22, 22 or magnets 23, 23 respectively. The magnets 22 when energized will close contacts 24, 24 to close the circuit 10 to the motor E to operate the latter in one direction, whereas the magnets 23, 23 as illustrated will close said circuit 10 through contacts 25, 25 to close said circuit to operate the motor E in the reverse direction. As will be understood the resulting operation will be that upon the operation of the generators C and D in the proper predetermined speed ratio there will be no current flow in the controlling circuit 4 and in consequence the switch arm 16 of a Thompson balance T or similar device will assume a neutral position as indicated, at which time the circuit 11 will be open and similarly the circuit 10 will be in normal open position whereby the controlling motor E will be unenergized. A variation in the rotating speeds of the generators C and D from that of the predetermined speed ratio will, as hereinbefore described, cause a current flow in the controlling circuit 4, the direction of which will determine the movement of the switch arm 16 to close the circuit 11 thereby to close the motor circuit E to operate the rheostat R in one direction or the other as governed by the relay switch devices shown. As will be understood the driving motors A and B may be of similar character, either a. c. or d. c. type, or may be energized by unlike circuits as desired. Also in similar manner the controlling generators and motors may be of either a. c. or d. c. type as may be desired.

In Fig. 3 a further suitable modified arrangement is shown wherein the motion for moving the controlling arm of the rheostat is derived from an independently and continuously driven motor G having its armature mounted upon and rotating a drive shaft 28 upon which are loosely mounted reversely arranged pinions 29 and 30 arranged to mesh with a gear 31 upon opposite sides thereof. The gear 31 is mounted upon a shaft 32 having a bevel gear 33 engaging a cooperating gear 34 to which the controlling arm 35 of the controlling rheostat R is affixed. Adjacent to each of the pinions 29 and 30, coupling elements 36 and 37 are slidably mounted upon the armature shaft 28 and rotatably secured thereto.

In this arrangement for operating the rheostat the controlling circuit through connection 4 is employed to effect the coupling of the armature shaft 28 with either the pinion 29 or pinion 30 to operate the rheostat in reverse direction dependent upon the direction of the flow of the current in the controlling circuit. This may be effected in any desirable manner, for instance through the instrumentality of a Thompson balance as described or similar device adapted to close a circuit through one or the other of contacts 36 and 37 to energize traction magnets 38 or 39 suitably connected

to the shiftable coupler elements 36 and 37 respectively. From the foregoing arrangement it will result that upon the closing of the circuits through either of the magnets 38 or 39 depending upon the direction of the controlling or differential circuit 4 the motor G will be coupled up to transmit its motion to the controlling arm of the rheostat in one direction or the other so as to increase or diminish the resistance value of the exciting field of the regulated motor.

While as hereinbefore described in my improved system of control it may preferably be arranged that the controlling means shall be operated in response to reversals of the flow of current in the controlling circuit 4 it will be obvious that the operating motor or the regulating rheostat may be made responsive to changes or variations in the value of the controlling circuit 4, so as to correspondingly adjust the rheostat. An arrangement of this character is shown diagrammatically in Fig. 4 wherein the arrangement is generally similar to that of Fig. 1 but wherein, as shown, mechanical means such as a weight 40 carried by a drum 41 rotatably connected to the rheostat arm is employed to be normally operative to move the rheostat arm in one direction. The voltage output of the generators C and D are suitably regulated by the rheostats r to establish a normal current flow in the controlling circuit 4 to energize the controlling motor E to produce a rotary effort in the opposite direction from that transmitted by the weight 40 and of a value under normal conditions to balance the effect of the weight 40. Thus upon the rotations of the respective driving motors A and B in their predetermined speed ratio a normal or balancing current flow will be established in the controlling circuit 4 with the result that the rheostat arm will remain stationary and any increase or decrease in the normal current flow in the controlling circuit 4 will create an unbalanced relation between the rotary efforts of the controlling motor E and the weight 40 resulting in a correcting movement of the rheostat arm in response to the unbalanced effort.

Also while I have illustrated in the hereinbefore described applications of my invention an arrangement wherein the controlling means is operative to maintain a fixed speed ratio by regulating the driving forces or energies of one of the motors only, it will be understood that the controlling means could be so arranged and connected to have a regulating effect upon both of the driving motors and in inverse relation. By way of illustration I have illustrated diagrammatically in Fig. 5 an application of my invention adapted to be so operative. A desirable manner of effecting my improved control by the regulation of both of the driving motors

as illustrated consists in the association of a second regulating rheostat 45 with the controlling motor E in addition to the rheostat R in an installation generally similar to that of Fig. 1. The rheostat arms of the respective rheostats R and 45 are connected to be moved in unison by the motor E under the influence of the controlling circuit 4 and connected to interpose resistance in the field exciting coils of the motor B and the rheostat 45 is similarly arranged in series with the field exciting circuit 46 of the driving motor A but reversed in its arrangement whereby it will act in inverse relation to that of the rheostat R with the result that upon the movement of the rheostat arms in unison the rheostats will act proportionately to increase the resistance in the exciting field of one driving motor and to decrease the resistance in the field exciting circuit of the other driving motor. It will thus be seen that in the approved modified form of my invention the differential or unbalanced pressures of the controlling circuit 4 will be operative to compensate for variations in the predetermined speed ratio by the regulation of both of the driving motors through the operation of the adjusting rheostats R and 45 connected therewith.

In accordance with further features of my invention I have shown in Fig. 6 a further application of my improved principle of operation for the control of independent driving means of rotary or centrifugal pumps in an arrangement whereby the differential pressures of the fluid are employed to actuate a controlling means of the character described. As diagrammatically shown, 50 and 51 are rotary pumps which may have their motors mounted directly upon the armature shafts of independently controlled driving motors as will be readily understood. Each of the pumps is provided with an outlet chamber 52, 52 through which the fluid passes in its flow to the outlet passages 54, 54 and communicating with each of these chambers 52 there is provided a cylinder 55. Within the cylinders there are pistons 56 movable therein under the action of the fluid pressures and the respective pistons 56 are connected as here indicated to operate rheostat arms 59 of generator rheostats 60, 60. In the present instance an arrangement is shown wherein the controlling generators C and D are mounted upon the armature shaft of a constant speed motor 62 and the output of the respective generators C and D are arranged to be proportionate to the operating speeds of the driving motors A and B by the regulation of the field exciting circuits of the generators. As here indicated the rheostats 60, 60 are each arranged in series with a field exciting circuit 64 and 65 for the respective generators C and D.

In the resulting operation the current flow in the controlling circuit 4 will be governed by the differential output of the respective generators C and D in response to the adjustment of the rheostat 60, which as indicated will vary the field excitation of the associated generators in response to the adjustment of the rheostat controller arms 59 under the action of the fluid pressures of the respective pumps 50 and 51 acting upon the pistons 56. The current flow in the circuit 4 is thus differentially produced and related to the operating speeds of the respective driving motors A and B operating the pumps 50 and 51 and will energize the controlling motor E. As hereinbefore described the controlling motor E is suitably connected whereby its torque will adjust the controlling arm of a controlling rheostat R connected in series with the field circuit of one of the driving motors, as here shown the motor B. It will therefore follow that the field excitation of the driving motor B will be automatically regulated in response to the differential current flow in the circuit 4 so as to regulate the driving forces of the motor B so as to compensate for any variations from the predetermined speed ratio. As will be understood in a generally similar manner my improved principles of control may be operative in response to differential pressures of other impelling forces, for instance steam or air.

As will be appreciated the features of my invention and improved principles of operation are susceptible of many and various modifications without departing from the substance of the invention as defined in the appended claims. As a further illustration thereof I have shown diagrammatically in Fig. 7 a further modified arrangement for producing the differential controlling circuit. As there indicated centrifugal governors 68 and 69 may be operatively connected to the respective driving motors A and B so as to be operative in proportion to the speeds of the latter. The governors 68 and 69 as indicated are suitably connected to actuate pivotal arms 71 and 72 of rheostats 73 and 74. The rheostats 73 and 74 are connected in parallel relation across the mains of a suitable circuit. The movable arms or contacts 71 and 72 at their outer ends contact with the respective rheostats 73 and 74 and are connected at their inner ends by the wires of a controlling circuit 4, the latter being thus closed in shunt arrangement between the parallel resistances or rheostats 73 and 74 and being adjustable with regard to the respective rheostats under the action of the independently operated governors 68 and 69.

The resulting operation will be that upon the maintaining of the proper relative speeds in the operation of the motors A and

B the movable contact 71 and 72 under the action of the governors 68 and 69 will assume corresponding positions with respect to their associated rheostats. Therefore, under the aforesaid conditions the resistances X-1 and X-3 interposed between the positive main 75 and the respective contact arms 71 and 72 will be balanced or of corresponding value whereby there will be no current flow in the differential circuit 4. Upon variation of the speeds of the motors A and B from that of the predetermined ratio the governors 68 and 69 will operate the movable contact arm 71 and 72 to assume unbalanced positions whereby there will be a potential drop therebetween in one direction or the other in proportion to the difference in the values of the portions X¹ and X³ of the respective rheostats. In other words when the position of the rheostat contact arms 71 and 72 are such that total resistance of the portions X¹ and X⁴ equal the total resistance of the portions X² and X³ upon opposite sides of the contact arms therefrom there will be no current flow in the controlling circuit 4. An increase of speed of the driving motor A will be operative to raise the rheostat contact arm 71 and correspondingly decrease the resistance through X¹ and establish a current flow through the controlling circuit 4 from that side of the line. In similar manner should the contact arm 72 be raised with relation to the position of the arm 71 there would be established a current flow in the opposite direction. The effect of the differential current in the circuit 4 so produced will be to energize the controlling motor E in the manner as heretofore described, the latter motor being connected to operate the regulating rheostat R arranged in series with the field exciting circuit of one of the driving motors. The differential controlling circuit 4 is thus made responsive to variations in the relative speeds of the driving motors A and B and operates through the rheostat R to compensate therefor.

In Fig. 8 I have shown diagrammatically a further system of my invention wherein a differential controlling circuit is arranged to effect the regulation of an additional circuit or source of energy to supplement a main supply circuit when desired. The improved arrangement now to be described is particularly desirable where an outside source of power is employed and where it is desirable to maintain the consumption of power from the outside source of a value not exceeding a predetermined volume. To be so operative it is arranged that when the consumption of power or load exceeds the normal the controlling circuit will be operative to control an independent generator or source of electrical energy whereby the latter will supply the amount of energy sufficient to

compensate for the peak of load and upon the falling off of the load below normal will be effective to diminish or cut out the current supply by the auxiliary circuit and to then employ the outside circuit alone to carry the full load.

In the approved arrangement or system shown diagrammatically in Fig. 8, C and D indicate two generators driven by a constant speed motor 78 and at 79 and 80 there are shown the field exciting circuits therefor. The circuits 79 and 80 of the generators C and D respectively are shown in arrangement with a field exciting circuit 81. In each of said field exciting circuits there is shown interposed a suitable adjustable resistance. As here shown the resistances may desirably be the usual compressible carbon resistance piles 84 and 20 connected in series with the circuits 79 and 80 respectively.

It is designed that the resistance 84 shall be adjustable in response to the load upon the total load circuit or mains 86 and that 25 the adjustment of resistance 85 shall be similarly responsive to the load upon an auxiliary or supplemental supply circuit 88 from an auxiliary or supplemental generator G which may be driven by any suitable 30 power such as a turbine 90. The supplemental circuit mains 88 are arranged in parallel relation with supply mains 91 from an outside or limited source of power. As will be understood the current supplied by the 35 outside mains 91 which may be termed the limited source of power may be purchased power supplied under contract, in connection with which it is desirable not to exceed a predetermined maximum load. The 40 supply mains 91 and supplemental supply mains 88 are connected with the total load mains 86 whereby the latter receives its total current supply from the circuits 88 and 91 and thus from the limited or outside source 45 of power or jointly from said source and from the supplemental generator G.

In accordance with my invention it is arranged that the operation of the supplemental generator G shall be responsive to fluctuations in the total load or mains 86 with respect to the circuit of the limited source of power. This result is accomplished through the instrumentality of a differential controlling circuit 4 connected to the respective controlling generators C and D. The current flow in the circuit 4 will be established in one direction or the other resulting from an unbalanced relation in the output of the generators C and D. The latter in turn will be 55 variable as aforesaid in response to the respective loads upon the total load mains 86 and auxiliary circuit 88. To be so responsive as indicated the resistance pile 84 is arranged to be compressible under the action

of an actuating magnet 92 energized by mains of series and shunt coils in circuits 93 and 94 connected with the total load mains 86. In similar arrangement the resistance 85 is compressible under the action of a magnet 95 energized by series and shunt coils 96 and 97 connected to the auxiliary supply mains 88.

A controlling motor E is arranged with its armature in circuit with the controlling circuit 4 whereby the motor E will be actuated in response to the current flow in the controlling circuit 4 resulting from the unbalanced pressures between the generators C and D. The controlling motor E is connected to actuate the controller arm 98 of the rheostat R connected in series with a field exciting circuit 99 of the supplemental generator G. Thus the output of the latter is regulated in response to the differential current flow in the controlling circuit 4. 85

The resulting operation is as follows: With the system set for the limit or capacity of power to be supplied by the external or limited source of power or mains 91, a change of load on the total load main 86 will 90 proportionately vary the strength of the field excitation of the generator C by adjusting the resistance 84 in the field circuit 79. The effect thereof will be to unbalance the voltage between the generators C and D 95 thereby causing a differential current flow therebetween. The current flow thus established will energize the controller motor E to rotate the rheostat controller arm 98 in a direction to change the value of the rheostat R to regulate the output of the supplemental generator G so as to take care of or compensate for the change in load on the main 86 and leave the demand on the mains 91 constant. In corresponding manner the 105 changes of load on the supplemental supply circuit 88 will vary the value of the field excitation of generator D by adjusting the resistance 85 in its field circuit. In consequence the voltage output of generator D 110 will be regulated under changes of load on the circuit 88 so as to restore the balance between the generators C and D and will correspondingly affect the action of the controlling motor E. The rheostat R will therefore be automatically controlled so that the current supply of generator G will be so regulated that it will take care of the peak loads or loads in excess of the capacity of the 115 external circuit 91 and will be variable in direct ratio with variations in the excess load below that of the capacity of the circuit 91 to effect the cutting out of the supplemental current supply circuit 88 to then employ the 120 outside circuit only to carry the full load.

As will be appreciated the principles of my improved system may be embodied in various modified arrangements without de-

parting from the invention. For instance a single but differentially wound controlling generator might be employed instead of the two generators C and D, with the field 5 citing circuits 79 and 80 connected substantially as indicated but with each of the differential windings. Furthermore it is obvious that if the supplemental generator G is of the a. c. type the controlling motor E 10 might be connected to control the engine or turbine driving said generator by regulating a valve thereof.

Having described my invention, I claim:—

1. In a system of the character described the combination of driving motors and machines independently driven thereby, of d. c. generators operatively connected with each of the driving motors and energized proportionate to the operating speeds thereof, a controlling-circuit connecting the respective generators and energized by variations in the respective generator circuits and controlling means arranged to be energized by the differential current in the controlling circuit, said controlling means being suitably connected to one of the driving motors to be operative to regulate the driving forces thereof so as to maintain constant a predetermined ratio in the operating speeds of the respective driving motors, substantially as described.
2. In a power transmission system of the character described the combination of independent electric driving motors, of electric generators operatively connected with each of the driving motors and adapted to generate currents of a value proportionate to the rotary speeds of the motor armatures, connections between the respective generators to establish a differential controlling circuit therebetween responsive to differences in the potential values of the respective generator circuits, a controlling rheostat arranged to interpose resistance in the field circuit of one of the driving motors, a controlling motor energized by the controlling motor to the rheostat whereby the latter is operated responsive to the current of the controlling circuit so as to adjust the field excitation of its associated motor so as to maintain a predetermined ratio in the operating speeds of the respective motors and the controlling motor having their field magnets separately excited from the same circuit so as to have a constant relative value of excitation and a rheostat arranged in series with the field coil of at least one of the generators to permit of adjustment to vary the speed ratio to be maintained, substantially as described.
3. In a power transmission system of the character described the combination of independent electric driving motors, of electric generators operatively connected with each of the driving motors and adapted to generate currents of a value proportionate to the rotary speeds of the motor armatures, connections between the respective genera-

tors to establish a differential controlling circuit therebetween responsive to differences in the potential values of the respective generator circuits, a controlling rheostat arranged to interpose resistance in the field circuit of one of the driving motors, a controlling motor energized by the controlling circuit, operating connections from said controlling motor to the rheostat whereby the latter is operated responsive to the current of the controlling circuit so as to maintain constant a predetermined ratio in the operating speeds of the respective motors, said generators being arranged to have their field magnets separately excited by currents of constant relative value and rheostats interposed in the field exciting circuits of said generators to permit of varying the relative values of the currents generated thereby to determine the ratio of speed to be maintained, substantially as described.

4. In a power transmission system of the character described the combination of independent electric driving motors, of electric generators operatively connected with each of the driving motors and adapted to generate currents of a value proportionate to the rotary speeds of the motor armatures, connections between the respective generators to establish a differential controlling circuit therebetween responsive to differences in the potential values of the respective generator circuits, a controlling rheostat arranged to interpose resistance in the field circuit of one of the driving motors, a controlling motor energized by the controlling motor to the rheostat whereby the latter is operated responsive to the current of the controlling circuit so as to adjust the field excitation of its associated motor so as to maintain a predetermined ratio in the operating speeds of the respective motors and

said generators and the controlling motor having their field magnets separately excited from the same circuit so as to have a constant relative value of excitation and a rheostat arranged in series with the field coil of at least one of the generators to permit of adjustment to vary the speed ratio to be maintained, substantially as described.

5. In a power transmission system of the character described the combination of independent electric driving motors, of electric generators operatively connected with each of the driving motors and adapted to generate currents of a value proportionate to the rotary speeds of the motor armatures, connections between the respective generators to establish a differential controlling circuit therebetween responsive to differences in the potential values of the respective generator circuits, a controlling rheostat arranged to interpose resistance in the field circuit of one of the driving motors, a controlling motor energized by the controlling

circuit, operating connections from said controlling motor to the rheostat whereby the latter is operated responsive to the current of the controlling circuit so as to adjust the field excitation of its associated motor so as to maintain constant a predetermined ratio

5 in the operating speeds of the respective

motors, said controlling motor and generators having their field magnets separately excited from a common circuit to have a 10 relatively constant value.

In testimony whereof I have signed my name to this specification.

HUGH NELSON HURD.
